(57) **CLAIM**

The ornamental design for an inspecting device for chips for casino, as shown and described.

DESCRIPTION

FIG. 1 is a front elevational view of an inspecting device for chips for casino showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front left side perspective view thereof;

FIG. 8 is a cross-sectional view taken along line A-A-in FIG. 5; and,

FIG. 9 is a cross-sectional view taken along line B-B in FIG. 5.

1 Claim, 6 Drawing Sheets

FIG. 1

FIG. 2

FIG. 3

FIG. 4

FIG. 5

FIG. 6

FIG. 7

FIG. 8

FIG. 9
